REGULATING SYSTEM

Application filed April 17, 1931, Serial No. 530,761, and in Germany April 25, 1930.

My invention relates to electrical regulators and has particular relation to regulators of the vibrating type which control auxiliary relays for controlling the effective value of a resistor.

In regulators of the vibrating type, relays controlled by the regulator are provided for the purpose of periodically short circuiting a portion of the shunt-field resistor of the machine being regulated, or of an exciter associated therewith, in response to changes in an electrical quantity, such as machine voltage, which changes affect the duration of time during which the continuously opening and closing, or vibrating, contact members of the regulator, disposed to control the relays, are in engagement.

It is general practice to energize the actuating coils of such relays from a direct-current-voltage source because, as is known, a uni-directional potential has many advantages for this purpose over an alternating-current voltage.

In alternating-current generator applications, direct-current for energizing the regulator relays is frequently obtained from the exciter, or from a separate battery or equivalent independent source. The use of either of these sources is, however, undesirable under some conditions.

If the exciter is employed for this purpose, provision must be made to compensate for the large variations in the exciter voltage which, as is well known, varies in accordance with the operation of the regulator. The compensating means must, therefore, prevent excessive current flow through the relay coils when the exciter voltage is high and insure sufficient current flow through the relay coils to operate the relays when the exciter voltage is low.

The utilization of a separate battery, or other external source of direct-current potential, while more satisfactory, is expensive if not required for other purposes.

Furthermore, when the vibrating contacts of the regulator, which control the intermediate relays, close a direct-current circuit, it is desirable that the polarity of the contacts be reversed occasionally to prevent one of

the contacts from becoming "pitted", and the other from "building up" in a non-uniform manner.

My invention is directed to a regulator system that avoids these and other difficulties. I attain the desired results by the provision of rectifying means for energizing the intermediate relays from the alternating-current machine or circuit, the voltage of which the regulator is disposed to maintain at a constant value.

It is, accordingly, an object of my invention to provide, in vibrating-type regulating systems for alternating-current circuits, means for energizing the actuating coils of the intermediate relays by direct-current of substantially constant voltage, derived from the alternating-current circuit.

It is a further object of my invention to eliminate the need for voltage-change-compensating means in the energizing circuits of the actuating coils of the intermediate relays of vibrating-type regulations.

An additional object of my invention is to provide, in a regulator of the type described, means for energizing the auxiliary relays which eliminates the need for reversing the polarity of the contact members of the regulator.

My invention, together with additional objects and advantages will best be understood from the following description of a specific embodiment thereof, when read in conjunction with the accompanying drawing, in which the single figure is a diagrammatic representation of apparatus organized in accordance with my invention as applied to a voltage regulator of the vibrating type, for governing the excitation of an alternating-current generator.

Referring to the drawing, a single-phase alternating-current generator 10 is connected to circuit conductors 11 and 12. The generator 10 is provided with a field winding 13 that is energized from any suitable source, such as an exciter generator 14, comprising an armature winding 15 and a field winding 16.

The exciter field winding 16 is connected to be energized from the armature 15 through

a circuit that includes a regulating resistor 17.

In order to maintain the voltage of generator 10 constant at a predetermined value, the vibrating-type regulator 18 is connected to be actuated in accordance with the voltage of the generator, to control the effective value of the resistor 17 by means of the relay 26.

The regulator 18 comprises a coil 19 that is connected to be energized in accordance with the voltage between conductors 11 and 12 through a potential transformer 20, and a coil 21 that is connected to be energized in accordance with the voltage across the field winding 13. Coils 19 and 21 of the regulator are associated with movable plunger elements, which respectively control, through the well known mechanical linkages shown, the positions of floating or vibrating contacts 22 and 23.

Regulatory action, in such a system, is accomplished by the periodic shunting of a section 24 of rheostat 17, in the exciter-field circuit, through the contacts 25 of an intermediate or auxiliary relay 26, which is disposed to operate in accordance with the opening and closing of vibrating contacts 22 and 23, in a well known manner. The usual polarity-reversing switch 27 is associated with contacts 25 of the intermediate relay. In case the system requires it, one or more additional auxiliary relays may be combined therewith, as relay 26' which is shown as connected in parallel circuit relation to the relay 26.

To supply the intermediate relay 26 with a direct-current voltage of substantially constant magnitude, I utilize a rectifier 28 connected, as shown, between the coil of the relay 26 and an alternating-current voltage, of suitable potential, derived from the generator circuit conductors 11 and 12, through the medium of transformer 30. It will be recognized that this arrangement makes possible the successful operation of relay 26 without the use of voltage-change-compensating means, which are necessary if the direct-current voltage is derived directly from the exciter terminals.

To make unnecessary the use of a polarity-reversing switch, in the circuit of the vibrating contacts 22 and 23, these contacts are, according to my invention, disposed to control the alternating-current input to rectifier 28, instead of the direct-current input circuit of the intermediate relays. In the embodiment shown, it will be seen that contacts 22 and 23 act to make and break the circuit through which transformer 30 energizes the rectifier, and, when so disposed, they pass alternating-current rather than direct current, as in all previous regulator connections known to me. Hence, they are not subjected to the undesirable and harmful material-transferring action which their use in a direct-current cir-

cuit involves, and polarity-reversing means may be dispensed with.

In operation of the regulating system, arranged as illustrated, the position of floating contact member 22 is determined by the voltage of generator 10, this contact member tending to move upwardly, away from the cooperating contact member 23, when the voltage is below normal, and downwardly, toward contact 23, when the voltage is above normal. The position of the floating contact member 23 is determined by the magnitude of the voltage of the exciter 14, high exciter voltages tending to bring it into engagement with contact 22 and low exciter voltages allowing it to move downwardly out of engagement therewith.

As is known, the contacts of a vibrating regulator of the type illustrated, alternately engage and separate. Engagement of the contacts 22 and 23 effects an operation of the relay 26 to increase the resistance in the exciter field circuit, and lower the voltage of the exciter 14. As the voltage of the exciter 14 and, consequently, of the generator 10, decreases, the energization of the windings 19 and 21 are both decreased to cause contact 22 to move upwardly and contact 23 to move downwardly, thereby effecting disengagement. This, in turn, acts to again decrease the resistance in the exciter field circuit, thereby causing the exciter voltage to again rise, and the operation just described is repeated to vary the effective value of the resistor 17 in accordance with the voltage of the generator 10.

In the system illustrated, closure of the vibrating contacts 22 and 23 impresses an alternating-current voltage between points 32 and 33 of the rectifier assembly 28. By action of the rectifier, this alternating-current voltage is converted into a pulsating direct-current voltage between points 34 and 35 thereof, which, in the particular arrangement shown, have relatively positive and negative potentials. This direct-current voltage energizes the actuating coil of the intermediate relays, 26 and 26', causing them to open their contacts and thereby remove the short circuit from section 24 of the resistor 17.

The increased resistance in the field circuit of the exciter lowers the current through field winding 16, thereby lowering the exciter voltage and causing contact 23 to move from engagement with the contact 22. This action will deenergize the rectifier 28 and control the relay 26, as described above.

In practice, rectifier 28 may be of any suitable type, preferably of the full-wave capacity. In my invention, I prefer to utilize the well known copper, copper-oxide disc type, which is schematically represented in the diagram. Each of the four branches there shown comprises a unit which is ca-

pable of conducting current only in the direction indicated by the arrows and the operation already described is thereby attained.

As is known, rectifiers of this construction are exceedingly reliable in their operation, since they are of a relatively simple and effective construction, and, furthermore, have the advantage of low cost and small maintenance.

10 It will be seen that the reliability of the system of my invention is exceedingly high, since the auxiliary relays are assured of a substantially constant direct-current voltage supply, so long as the alternating-current generator being regulated continues in normal operation. Failure of the generator voltage, therefore, is practically the only condition under which the supply for the auxiliary relays would be cut off, in which 15 case, no damage could result.

10 It will be seen that, through the system of my invention, I have provided a simple, effective and highly reliable means of supplying a direct-current voltage to the auxiliary relays of vibrating-type regulators when applied to alternating-current machines or circuits, which, in addition, eliminates the need for the usual polarity-reversing switch in connection with the floating contacts of 20 the regulator.

Although I have shown and described a specific embodiment of my invention, I am fully aware that many modifications thereof are possible. My invention, therefore, is 25 not to be restricted except insofar as is necessitated by the prior art and by the spirit of the appended claims.

I claim as my invention:

1. In a regulator system, an alternating-current circuit and a generator connected thereto, means for governing the excitation of said generator comprising a resistor, a regulator having vibrating contact members actuated in accordance with the voltage of 40 said circuit, a rectifier energized from an alternating-current source in accordance with the action of said regulator, and a relay energized by direct current from said rectifier for controlling the effective value of said resistor.

2. In a regulator system, an alternating-current circuit, and a generator connected thereto, provided with a field winding, means for governing the excitation of said generator comprising a regulator actuated in accordance with the voltage of said circuit, a rectifier energized from an alternating-current source in accordance with the action of 55 said regulator, and means energized by direct current from said rectifier for controlling the energization of said field winding.

3. In a regulator system, an alternating-current circuit and a generator connected thereto, means for governing the excitation of 60 said generator comprising a regulator of the

vibrating type and a resistor controlled thereby, relays for effecting said control of the resistor, and means for energizing said relays from the alternating-current circuit comprising a current rectifier disposed intermediate said circuit and the relays.

4. In alternating-current circuit regulating systems of the vibrating type comprising voltage-adjusting means, relays disposed to act upon said adjusting means, and regulator contact members responsive to the voltage of said circuit and disposed to control the actuation of said relays, means for energizing the said relays from the circuit voltage which the regulator maintains constant, said means comprising a current-rectifier and connecting circuits therefor so disposed that the said regulator contact members are connected ahead of the rectifier to thus act in the alternating-current connecting circuit.

5. In a regulator for maintaining a source of alternating-current voltage of desired potential comprising, in combination, vibrating contact members and auxiliary relays controlled thereby, means for energizing said auxiliary relays from said alternating-current voltage source comprising a current-rectifying device disposed in a connection between said voltage source and said relays to supply a substantially constant direct-current voltage thereto.

6. In a regulator for an alternating-current voltage source, the combination comprising auxiliary relays, vibrating-contact control means therefor, and a current rectifier disposed in a connection between said alternating-current voltage source and said auxiliary relays to supply thereto a direct-current energizing voltage.

7. In combination, an alternating-current generator provided with a field winding and a direct-current exciter therefor, a shunt field winding for said exciter and a resistance in series circuit therewith, one or more relays for short-circuiting portions of said resistance, an energizing circuit for said relays, a current rectifier in said circuit disposed for energization from said alternating-current generator, and vibrating-contact regulator-control means actuated in accordance with the voltage of said generator and disposed to control said energization of the rectifier.

8. In combination, an alternating-current generator, an exciting winding therefor, a direct-current generator for energizing said exciting winding, a shunt field winding for said direct-current generator, a resistance in series with said shunt field winding, one or more relays for short-circuiting said resistance, vibrating contact members actuated in accordance with the voltage of said generator for controlling said relays, and means for energizing, by a direct-current voltage, said relays from the voltage of said alternating-current generator, said means comprising a

current-rectifying device and circuits associated therewith.

9. In combination with an alternating-current generator and a regulator comprising cooperating contact members, windings for causing said contacts to engage and be disengaged, and auxiliary relays controlled by said contact members, a current-rectifying device, and means for connecting said device between said generator and said auxiliary relays, said current rectifier functioning to supply a direct-current energizing voltage to the relays.

10. In a vibrating-type regulator for governing the field excitation of an alternating-current dynamo-electric machine in response to the voltage variation of said machine, the combination comprising vibrating contact members, a machine-excitation-controlling resistor, a plurality of relays of the direct-current type disposed to short circuit sections of said resistor, a current rectifier energized from the voltage of said alternating-current machine in accordance with the action of said vibrating-contact members of the regulator, and means whereby said relays are energized by direct-current from said rectifier.

In testimony whereof, I have hereunto subscribed my name this 4th day of March 1931.

ERNST GRAU.
